UNITED STATES PATENT OFFICE.

HARVEY N. CARPENTER, OF PHILADELPHIA, PENNSYLVANIA.

PAPER BOX.

SPECIFICATION forming part of Letters Patent No. 339,147, dated April 6, 1886.

Application filed February 10, 1886. Serial No. 191,483. (Model.)

To all whom it may concern:

Be it known that I, HARVEY NELSON CARPENTER, a citizen of the United States, residing at Philadelphia, Pennsylvania, have 5 invented a new and useful Improvement in Boxes Made of Paper or other Suitable Materials, of which the following is a specification.

My invention relates to an improvement in 10 boxes made of paper, pasteboard, enameled card-board, sheet-lead, or other suitable material, the object being to so construct a box cut in the proper form, that the ends thereof may be easily and readily folded, and at the 15 same time effectually prevent the escape or sifting of any contents thereof.

My invention consists of certain novel features in the construction of the flaps forming the top and bottom of said box. The top and 20 bottom of the box are alike, and therefore the accompanying drawings show only the body of the box and the top thereof.

Figure 1 is a perspective view of my improved box with the top thereof open, showing the various flaps and lines. Fig. 2 is a similar view with a small portion of flap C uncovered and flap E drawn back to show the lock made by lips L and M. Fig. 3 is also a perspective view of the box closed, showing 30 end F slipped through slit O.

A represents the body of a box, of any suitable form and material, sealed along one side vertically, leaving the end open for filling or emptying, as desired.

35 B and C are flaps on opposite sides of the box, folding on lines T Y and T² Y², respectively. Flaps B and C are extended, forming lips M and L, which fold on lines R S and R' S', respectively. The other two flaps of the 40 box, D and E, fold on lines T T² and Y Y². Flap D has an end or tongue, F, and is also cut to form curbs G and H, which fold on lines T R, T X, and X' T' R', as plainly shown in Fig. 2. Flap E is also so cut as to form 45 rounded lips N and N', which fold on lines Z' Z² and Z' Z², respectively, and curbs K and K', which fold on lines Y' Z², Y S, and Y' Z², Y' S', respectively. The flap E has also the horizontal slit O.

50 The ends of the box may be folded according to my invention by first folding inward

flap B, the fold being on lines T Y, T X, Y Z², T R, Y S, said flap when thus folded lying flat upon the contents of the box, but covering but about one-half of the top thereof, the lip M, 55 folding on lines R S, then assuming an upright position at right angles to the flap B. In thus closing the flap B the curbs G and K, folding on lines T R and F X and Y S and Y Z², respectively, are drawn in and lie or fold 60 flat against a portion of the flaps D and E, respectively. The flap C is then folded on the lines T² Y², T² X', Y² Z², T² R', Y² S', said flap then covering the other portion of the top of the box not covered by the flap B, as stated, 65 and likewise lying flat on the contents of the box, having the lip L first slipped under the lip M, thus forming a tight and complete center crosswise lock.

In folding flap C curbs H and K', folding on 70 lines T² R', T² X', and Y² S', Y² Z² are drawn in and likewise lie flat against the portion of the flaps D and E, as shown in Fig. 2. The flap D is then folded inward on lines T T², T X, T² X' far enough to allow the tongue F, 75 which is brought forward for that purpose, to be run upward through the slit O in flap E, which is also folded inward on the lines Y Y², Y Z², Y' Z². As the tongue F slips through opening O the curved lips N and N', folding 80 on lines Z² Z⁴, Z' Z², respectively, gradually are slipped under the curbs G, along the line T X and curb H, along the line T² X', the flap D of course being under the flap E. These two flaps are then gradually tightened by 85 drawing tongue F tighter through O, and thus causing lips N and N' to embrace curbs or parts G and H, as indicated. The whole is then pressed together, thus completing a durable, tight, and ready cover for the box, which 90 can be opened with ease. Paste or other adhesive substance may be applied to the upper inner end of tongue F, (if necessary, also to the inner ends of lips N and N'), causing F to retain a more permanent position. 95

The lips N and N' may be omitted, and I may not pass the tongue F through the flap E, but fold the flap E before the flap D, and by the use of paste, in the usual way, cause the tongue to retain its position.

100 My box is preferably used with a tin-foil or waxed or oiled paper or sheet-lead lining made

in the shape and form of the box, and when thus lined the box is practically water-tight, excluding all dampness, and also preventing the escape of any of the inclosed material, and is therefore of great value to shippers of seed, to druggists, and others engaged in mercantile pursuits.

Should I make the box out of sheet-lead, thin strong paper of any suitable material may 10 be used as a lining therefor.

Having described my invention, what I claim as new, and desire to secure by Letters Patent, is—

1. A box of paper, pasteboard, enameled 15 card-board, sheet-lead, or other suitable material, having a lining cut to match said box, made of the material specified, having flaps B and C, with lips M and L, moving on lines R S and R' S', respectively, and the curbs or 20 smaller flaps G and K H and K', said flaps B C being bent to fold on lines T Y, T X, Y Z³, T R, Y S, and Y² T², Y² S', Y² Z² T² R', T² X', re-

spectively, curbs G and K, folding on lines T R, T X, and Y Z³, Y S, respectively, and the other of said curbs, H and K', folding on lines 25 T² R', T² X', and Y² Z², Y² S', respectively, in combination with each other and flaps D and E, the whole being arranged to close substantially as described and set forth.

2. In a box of any suitable form and material, the flap D, bent to fold on line T T², T X, T² X', with end or tongue F, and flap E, bent to fold on line Y Y², Y Z³, Y² Z², with curved lips N and N', folding on lines Z³ Z⁴, Z' Z², with slip or opening O, in combination with curbs 30 K and K', and flaps D, and curbs G and H, and flaps B and C, substantially as and for the purpose described.

Signed at Philadelphia, Pennsylvania, this 23d day of November; A. D. 1885.

HARVEY N. CARPENTER.
